UNITED STATES PATENT OFFICE.

JOHN R. VAN DAME, OF GRAND RAPIDS, MICHIGAN.

TAILOR'S CHART.

SPECIFICATION forming part of Letters Patent No. 790,333, dated May 23, 1905.

Application filed February 25, 1904. Serial No. 195,302.

To all whom it may concern:

Be it known that I, JOHN R. VAN DAME, a citizen of the United States, residing at Grand Rapids, in the county of Kent and State of Michigan, have invented certain new and useful Improvements in Tailor Systems, of which the following is a specification.

My invention relates to improvements in charts for use in ladies' tailoring; and its object is to provide a chart with which the several points of measuring and positions of lines may be readily established for the use of the tailor-square. I attain this object by the construction and delineation shown in the accompanying drawings, in which—

Figure 1 is a plan of the back portion of the chart. Fig. 2 is a plan of the front portion of the chart. Figs. 3 and 4 are plans of the reverse sides of the square used with this chart, patented to me October 25, 1898, and not subject of invention in this application; and Fig. 5 is an outline of a bust, showing the two bust-measurers.

Similar letters and numerals of reference represent similar parts throughout the several views, it being distinctly understood that the fixed numerals and characters are not to be applied as references except where hereinafter distinctly mentioned for reference.

The border spaces and numerals upon the chart correspond with similar spaces and numerals upon the square and are designed wholly to express measurements, &c., and as the description of one measurement will illustrate all I will confine myself to a single description upon each portion of the chart.

As Fig. 1 illustrates the back portion of the chart, I will first complete the description of this section of the chart. Place the chart Fig. 1 upon the fabric to be cut, first having taken the proper and necessary measurements of the person to be fitted, and draw line 11' across the top of the chart. Then make a **V** at 12' for width of back-measure, and at 13' for neck-measure. Draw line 2' down the full length of the chart and make **V** at 15' for length of back-measure, also at N' for neck-measure, and at A' on line 11 for length of arms-eye. Make a **V** at 36' for bust-measure and draw line 3 to finger-point

at 24'. Slide the chart to the right until the point E stops at 36' (which carries the point 15' to 15'') and draw a line from 36' to D' at right angles with line 3'. Now move the chart back to the left until the point 15' rests at 55 12' and draw line 5' to line 3'. The chart is now laid aside and with the square place N, Fig. 4, upon N', Fig. 1, and draw the neck-line N' 13'. Now place I, Fig. 4, at J, Fig. 1, and draw the curved line 8 from J to the slot at 32'. To draw the waist-line 9, place point A of the square at D' and draw line 9. Place the point 24 on the square at C' on the chart and make a **V**. Slide the square to the right until A rests at C' and mark at F' one inch to 65 the right of C', and from 24 on the square mark H'. Now mark N'' one inch to the left of 15', and B' two inches to the left of 15'. Draw line 10 from N' to N'' for sewing-line, and then mark line 11 from A' to 24', where 70 it joins line 3'. Now place the point B on the square at B, Fig. 1, and draw the line 13 from B to B'. Place point C of the square at C, Fig. 1, and draw line 12 from C to C'. Place the point H of the square at H on Fig. 1 and draw line 14 75 to H'. For line 15 place E of the square at F on line 8 and draw the line to F' on line 9. For line 16 place the point D on the square at D' and draw the line to D''. The lines below the waist-line (line 9) are drawn substantially as shown in Fig. 1.

Coming now to the front section of the chart Fig. 2, place the chart upon the article to be cut, first having taken the necessary measurements of the person being fitted, and 85 check off the dimensions, as indicated at the several **V** marks. Draw line 1 the full length of the chart and make a **V** at 15, at A, at 13, and at N on this line. Draw line 2 across the top of the chart and make a **V** at D, at W, at 90 R, and at T and mark through perforations at O' P' for top darts. Now using the perforation 28 on line 3 as a pivot, swing the chart to the position of the dotted lines 17' X and mark a **V** at 36, slide the chart to the left 95 until the corner 46 rests at 36, and draw the line 4' from 36 to 8, practically at right angles with the dotted outlines of line 3. Now swing the chart to its normal position and slide it to the left until the point T stands at R and 100

draw the chest-line I' and mark a **V** at S . Raise the chart until the lower left-hand corner rests at 15, and draw the waist-line 15 15", marking for dart-lines at O , P , Q' , and Q . Now place 5 the point 24 on line 6 at Q' to locate the points of line 8 Q . Lay the chart aside and with a tape-measure pivoted at N describe the neck-line W 13 from D , describe the top of dart-lines 36 and 39, and from W the waist-lines, line 10 6 and line 15 15", may, if desired, be described. With the square place the point H at O' with the curve to the left and make the line $O' O$. With H at P' make the line $P' Q'$ for the left sides of dart-openings. Reverse the square and 15 place the point I at O' to form the line $O' P$ and at P' to form the line $P' Q$ for the right-hand side of the dart-openings. Place point C of the square at 13" and point H of square upon the front line and draw the front line 20 13" of the garment for the sewing-line. Place the point J of the square upon W and draw the line $W S$, reverse the square, with point K at S' one-half inch down, and draw a line intersecting the shoulder-line at the chest-line I' , as shown. Draw the arms-eye curve with the arms eye-curve J' of the square by placing F of the square upon line 3 and L on the square to the chest-line I' . Then slide the square up one-half inch and complete the 25 curve to S' , substantially as indicated in Fig. 2. The important feature with this chart is the means for finding the neck-line W 13 and the back-line $4'$ not available with any other system. For this purpose we take first the long 30 bust-line $a b$, Fig. 5, and then the short bust-line $a c$, and a direct line through b and c will give the exact point for neck-line at W , Fig. 2, and by carrying the lower end of the chart back the exact distance of the difference be-

tween these measurements, pivoting at 28, say, 40 to 17', will throw line 3 to the exact position to locate line $4'$, which, as hereinbefore stated, is practically at right angles with the changed position of line 3 (indicated by the dotted lines) and is said to balance with the point W . 45

The hereinbefore-described method of finding the proper points and lines in patterning-cutting may be applied to any combination of measurements indicated by the several scales upon the chart. 50

The lines below the waist-lines are carried down by use of the square, substantially as shown upon the chart.

Having thus fully described my invention, what I claim as new, and desire to secure by 55 Letters Patent of the United States, is—

In a tailor's chart, a waist and a bust portion the back of the waist portion extending beyond the back of the bust portion and separated for a distance from the bust portion by 60 a slot between the two, graduated scales upon the front, upon a portion of the back, upon the waist-line and upon the top of the waist, fixed points from which to strike the dart-lines, vertical lines upon the bust portion 65 for establishing the chest-line and arms-eye curve, fixed point upon the waist portion for striking the neck-line, the top of dart-line and the waist-line, and a fixed pivot-point from which the back of neck-line and the back of 70 waist-line are established, substantially as and for the purpose set forth.

Signed at Grand Rapids, Michigan, February 20, 1904.

JOHN R. VAN DAME.

In presence of—

C. V. CILLEY,
ITHIEL J. CILLEY.
